CLAIM

The ornamental design for a combined baby bottle and disposable liner, as shown and described.

DESCRIPTION

FIG. 1 is a front elevational view of a combined baby bottle and disposable liner, showing my new design, with all sides being identical to that shown;

FIG. 2 is a top plan view thereof; and

FIG. 3 is a bottom plan view thereof.
